CLAIM

The ornamental design for an ear piece holder, as shown and described.

DESCRIPTION

FIG. 1 is a perspective view of an ear piece holder, FIG. 2 is a front view of the ear piece holder shown in FIG. 1, FIG. 3 is a rear view of the ear piece holder shown in FIG. 2, FIG. 4 is a top view of the ear piece holder shown in FIG. 2, FIG. 5 is a bottom view of the ear piece holder as shown in FIG. 2, FIG. 6 is a right side view of the ear piece holder as shown in FIG. 2; and, FIG. 7 is a left side view of the ear piece holder as shown in FIG. 2.

The ear piece holder is attached for example to a dashboard for supporting an earpiece of a telephone, a hearing aid or other small equipment in a convenient position, where it can easily be found and retrieved when needed.
